CORSET WITH ELASTIC INSERT

Fanny Jackel, Bronx, N. Y.

Application February 25, 1950, Serial No. 146,307

5 Claims. (Cl. 2-27)

1

The present invention is directed to corsets, more particularly to a type wherein elastic members are provided.

Many forms of corsets have been and are being used. They are intended to improve the figure of the wearer, and in particular to confine the abdominal region so as to make the wearer appear more slender than she actually is. Accordingly, various mechanical constructions of corsets have been devised utilizing elastic inserts in the body thereof. Some of them were sufficient to accomplish at least part of the desired result but many of them were uncomfortable and placed such great stress on the corset that they easily tore or ripped.

The present invention is intended and adapted to overcome the difficulties and disadvantages inherent in prior devices of the type described, it being among the objects of the present invention to provide a corset which may be readily put on and taken off and which is comfortable to the wearer.

It is also among the objects of the present invention to provide a corset which gives adequate support to the body at the areas where it is most needed, and particularly in the abdominal region.

It is further among the objects of the present invention to provide a structure of corset which is relatively simple, which is relatively inexpensive to produce and which is sufficiently strong and sturdy so that it is not subject to premature wearing out.

In practicing the present invention there is provided a corset of the usual construction, and particularly one in which inserts of an elastic woven fabric such as those containing threads of rubber or the like are used. Within the front of the corset is introduced a panel made of woven fabric which is not elastic. This panel is adapted to cover the abdominal area. On opposite edges of the central panel are provided a plurality of elastic bands of substantial width. The inner ends of the bands are secured to the edges of the panel and the outer ends are secured to the sides of the corset, usually in front of the hip bones. The panel itself is free from attachment to the corset.

Usually there are four elastic bands at each edge of the central panel. The upper two bands overlap and extend downwardly and outwardly from the panel and the two lower bands also overlap each other and the upper bands and extend upwardly and outwardly.

By reason of this arrangement, the central panel tends to hold the abdominal area flat due

2

to the tension of the bands. The upper bands tend to hold the abdominal area from creeping upward and the lower bands prevent it from extending downward. The structure of the corset is such that when it fits snugly, the bands are in extended positions and exert compressive forces on the abdominal area. As a result, there is a uniform distribution of this area and bulging is practically eliminated.

10 In the accompanying drawing constituting a part hereof and in which like reference characters indicate like parts,

Fig. 1 is a front view of a corset made in accordance with the present invention;

15 Fig. 2 is a rear view thereof;

Fig. 3 is a fragmentary enlarged view of the inside of the front of the corset, showing the panel and bands in position;

20 Fig. 4 is a fragmentary view of one edge of the panel showing the relative positions of the bands, and

Fig. 5 is a horizontal cross-sectional view taken along the line 5-5 of Fig. 3.

The front 1 of the corset has a pair of gores 2 at the lower edge thereof made of an elastic fabric containing rubber threads such as "Lastex" material. Along the edges of front 1 are strips 3 of similar elastic material. Back 4 has a gore 5 at the upper edge thereof and strips 6 of elastic material along the sides. Fabric pieces 7 connect the front and rear portions of the corset. A zipper 8 is provided at one side for opening and closing the corset.

As shown more particularly in Figs. 3 and 4, a 35 rectangular panel 10 of inelastic woven fabric of rectangular form is provided. Upper edge 11 extends slightly above the waist line and lower edge 12 is of a shallow V-shape. A pair of relatively wide elastic bands 13 and 14 are provided at the 40 edges of the upper portion of panel 10, said bands overlapping each other and extending downwardly and outwardly. Similarly a pair of relatively wide elastic bands 15 and 16 are attached to the lower portion of the edges of panel 10 and 45 extend upwardly and outwardly. Band 15 underlays bands 13 and 14 and band 16 overlays band 14. All of the bands are stitched to the panel along the lines 17 and 18. The outer edges of the bands are stitched to member 7 at lines 19 and 20. The waistline of the garment is shown at 21.

50 Although the invention has been described setting forth a single specific embodiment thereof, various changes in the details of construction 55 may be made within the spirit of the invention.

For instance, instead of having four elastic bands on each side of panel 10, a lesser number may be used or a greater number may be provided. It is essential that the slope of the bands be maintained. For instance, there may be two upper elastic bands and one lower, or vice versa. Seams 19 and 20 need not be made on member 7 but the bands may be directly stitched to the elastic fabric 6. Instead of Lastex fabric, a knitted elastic material may be used. The panel-and-band insert may be placed in other positions within the corset than shown, and it may be reversed. The bands may be overlapped in a different sequence than shown. The insert may have its edges stitched together before assembling into the corset or a tape may be stitched to said edges. The insert may be fitted into other types of corsets than shown herein. In Fig. 5, front 1 has been shown as of substantially greater width than the panel and bands. This permits a considerable amount of stretching of the bands but the looseness of panel 10 may be varied to a considerable degree, depending upon the person to be fitted.

These and other changes may be made in the details of the invention, which is to be broadly construed and not to be limited except by the character of the claims appended hereto.

I claim:

1. In a corset having front and rear body portions and stretchable members therein, said front and rear portions being joined together at the sides of said corset, the improvement which comprises a front central woven fabric panel on the inner face of said corset and adapted to cover the abdominal area, a plurality of elastic bands within the inner face of said corset having their inner ends stitched to the opposite side edges of said panel and their outer ends stitched directly to the opposite sides of said corset at the junction of the front and back thereof, said bands overlapping, at least one upper band extending downwardly and outwardly from the upper portion of said panel and at least one lower band extending upwardly and outwardly from the lower portion of said panel, said panel being free from attachment to said corset.

2. In a corset having front and rear body portions and stretchable members therein, said front and rear portions being joined together at the sides of said corset, the improvement which comprises a front central woven fabric panel on the inner face of said corset and adapted to cover the abdominal area, a plurality of elastic bands within the inner face of said corset having their inner ends stitched to the opposite side edges of said panel and their outer ends stitched directly to the opposite sides of said corset at the junction of the front and back thereof, said bands overlapping, at least one upper band extending downwardly and outwardly from the upper portion of said panel and at least one lower band extending upwardly and outwardly from the lower portion of said panel, said panel being free from attachment to said corset, the width of said panel and bands being less than the width of the front of said corset.

3. In a corset having front and rear body portions and stretchable members therein, said front and rear portions being joined together at the sides of said corset, the improvement which comprises a front central woven fabric panel adapted

to cover the abdominal area, a plurality of elastic bands having their inner ends secured to the opposite side edges of said panel and their outer ends secured to the opposite sides of said corset at the junction of the front and back thereof, said bands overlapping, at least one upper band extending downwardly and outwardly from the upper portion of said panel and at least one lower band extending upwardly and outwardly from the lower portion of said panel, said panel being free from attachment to said corset, the width of said panel and bands being less than the width of the front of said corset, there being two upper and two lower bands, the two upper bands being in contact and the two lower bands being in contact with opposite faces of said upper bands.

4. In a corset having front and rear body portions and stretchable members therein, said front and rear portions being joined together at the sides of said corset, the improvement which comprises a front central woven fabric panel adapted to cover the abdominal area, a plurality of elastic bands having their inner ends secured to the opposite side edges of said panel and their outer ends secured to the opposite sides of said corset at the junction of the front and back thereof, said bands overlapping, at least one upper band extending downwardly and outwardly from the upper portion of said panel and at least one lower band extending upwardly and outwardly from the lower portion of said panel, said panel being free from attachment to said corset, the width of said panel and bands being less than the width of the front of said corset, there being two upper and two lower bands, the two upper bands being in contact and the two lower bands being in contact with opposite faces of said upper bands, one side of said corset being open and cooperating fasteners in said opening.

5. In a corset having front and rear body portions and stretchable members therein, said front and rear portions being joined together at the sides of said corset, the improvement which comprises a front central woven fabric panel on the inner face of said corset and adapted to cover the abdominal area, a plurality of elastic bands within the inner face of said corset having their inner ends stitched to the opposite side edges of said panel and their outer ends stitched directly to the opposite sides of said corset at the junction of the front and back thereof, said bands overlapping, at least one upper band extending downwardly and outwardly from the upper portion of said panel and at least one lower band extending upwardly and outwardly from the lower portion of said panel.
